UNITED STATES PATENT OFFICE.

ARTHUR E. ARNOLD, OF LLANDUDNO, WALES.

COAL CABINET, SCUTTLE, AND THE LIKE.

1,350,913.

Specification of Letters Patent. Patented Aug. 24, 1920.

Application filed October 23, 1919. Serial No. 332,728.

To all whom it may concern:

Be it known that I, ARTHUR EDMUND ARNOLD, a subject of His Majesty the King of England, and resident of Llandudno, in the county of Carnarvon, Principality of Wales, have invented certain new and useful Improvements in or Connected with Coal Cabinets, Scuttles, and the like, of which the following is a specification.

10 This invention relates to coal cabinets, scuttles, and the like.

The invention has for its primary object to provide an improved coal cabinet, scuttle or box which is highly efficient in use, can be easily and quickly filled or loaded, and from which the coal can be removed for use with much greater facility than with the cabinet scuttles and boxes heretofore provided.

20 Another important object of the invention is to provide a cabinet, scuttle or box from which a shovelful or small quantity of coal can be removed without having to tip over and support the whole weight of the cabinet, 25 scuttle or box and its contents or to remove said shovel from the bulk of the coal, which procedure nearly always entails a considerable amount of labor and strength and is often attended by the upsetting of small 30 pieces of coal or coal dust out of the container onto the floor.

According to the invention the improved cabinet, scuttle or box comprises a compartment to receive the bulk of the coal and a 35 device adapted to communicate with said compartment and receive therefrom a more or less small or moderate and measured or restricted quantity of coal, from which device the coal is removed as and when required, 40 said device being automatically refilled from the compartment after each use of the cabinet, scuttle or box and each removal of coal therefrom.

In order that the invention may be more 45 clearly understood and more readily carried into effect, it is hereinafter described with reference to the accompanying drawing, in which:—

Figure 1 is a sectional side elevation of a 50 coal cabinet or scuttle, and

Fig. 2 is a perspective view of same.

Fig. 3 is a section through the door, showing the means for supporting the coal box.

As shown and in a suitable manner of 55 carrying out the invention in connection with a coal cabinet the same comprises a

wooden or other cabinet proper or case *a* the front of which is formed with two openings disposed one above the other, and in each of said openings is fitted a door or flap *b* and *c* which is pivoted at *b'* *c'* respectively to the sides of the cabinet or case *a* so as to open vertically and swing outwardly and downwardly to a limited extent approximately to a horizontal position, as shown in dotted lines in the drawing.

A stationary wooden or other baffle or shelf *d* is fitted within the cabinet or case, inclines as shown downwardly and rearwardly, and extends across the interior of said cabinet or case *a* and from a point near the lower edge *b''* of the upper opening to a point disposed half-way or thereabout, between the front and rear of the said cabinet or case. The upper door or flap *b* is adapted to support a coal box or receptacle *e* which is preferably formed as a separate article and designed, after having been filled with coal, to be slid into position on said door or flap *b* when the latter is open or pulled out. To facilitate the positioning of the coal box or receptacle *e* upon the door or flap the upper surface of the latter may although not as shown, be fitted with a number of rollers upon which said coal box or receptacle can run. As shown in Fig. 3 the door *b* is shown as provided with offset flanges *f'*, to slidably receive lips *f''*, the bottom of the box resting against block *f*, to retain and support the coal box or receptacle *e* on the door. If desired, however, the coal box or receptacle may be permanently secured to the door or flap.

When the upper door of the flap *b* is closed the coal falls out of the coal box or receptacle *e* into a compartment *g* formed by the major portion of the interior of the cabinet or case and onto a second stationary baffle or shelf *h* serving as the bottom of said compartment, which baffle or shelf *h* extends across said interior of the cabinet or case *a* and inclines as shown forwardly and downwardly and from the rear of same to a point disposed toward the front of the cabinet or case.

On the inside of the lower door or flap *c* is provided a measuring device consisting of a portion of said door or flap *c*, side plates *i*, an inclined false bottom plate *j* and a rear arcuate plate *k* curved on a radius having for its center the axis of the pivots *c'* of the door or flap *c*. When the door or

flap *c* is closed the upper edge of the arcuate plate coincides as shown with the lower or front edge of the lower baffle or shelf *h*, and as said door or flap *c* is opened said arcuate plate *k* moves upward and its outer surface remains in running contact with or in close proximity to said edge. With this construction it will be appreciated that in the normal closed position of the lower door or flap 5 the measuring device is disposed within the cabinet or case *a* and in open communication with the main compartment *g* and the bulk of the coal therein and thus a limited amount of coal, determined by the capacity 10 of said device, falls into the latter from said compartment and the lower baffle or shelf. As the door or flap *c* is opened and the measuring device is moved outward the rear arcuate plate *k* isolates and cuts off the 15 contents of said device from the bulk of the coal in the main compartment and prevents said bulk falling out of the cabinet or case. In the open position the measuring device shown in dotted lines, all or the major portion 20 of the coal therein can be easily removed with a shovel, the door or flap *c* serving as a convenient shoveling platform. When the door or flap *c* is again closed another limited quantity of coal automatically 25 slides down the lower baffle or shelf *h* into the measuring device in readiness for the next shoveling operation, and this procedure continues as often as it is required to remove a limited quantity of coal from the 30 cabinet or case and until the latter is empty. 35 A drawer *l* is preferably fitted in the cabinet or case and under the measuring device to catch any coal dust that may find its way downward past the arcuate plate *k* and/or other parts of said device. Also a shelf *m* is fitted inside the lower portion of the cabinet to hold a shovel *n* so that it can be easily reached when the lower door is opened. 40 45 If desired more than two inclined baffles or plates may be provided within the cabinet or case *a* to check the fall of the coal from the coal box or receptacle and into the main compartment and the measuring device and to locate it within said compartment. One or more spring-controlled and pivoted or slidable plates, and/or one or more fixed vertical plates may be provided within the cabinet or case, such as 50 on the lower or inner edge of the upper baffle or shelf, to stack the coal within the 55

cabinet or case and thus increase the capacity of the latter without interfering with the free movement of the coal into the measuring device. Other modifications may 60 be made in the general construction and arrangement of parts of the improved cabinet, scuttle or box without departing from the principles of the invention set out above. 65

What I claim is:—

1. A coal cabinet having an upper opening provided with a closure, a main coal receptacle supported on said closure, said cabinet having a lower opening provided with a closure, a coal receiving member supported on, and movable with, said lower closure, and an inclined baffle arranged in the cabinet to receive material from the receptacle on the upper closure, and deliver said material to the coal receiving member. 70 75

2. A coal cabinet formed with upper and lower openings provided with swinging closures, a main coal box carried by the upper closure, and having an opening to deliver the material from said box when the latter is within the cabinet, a baffle plate arranged in the cabinet below said main coal box, and adapted to receive the material from the latter, and a coal receiving member carried by the lower closure, and movable therewith, said member being movable into and out of a position relative to the baffle to receive a quantity of coal from such baffle and to serve as a cut off for coal delivery from the baffle. 80 85 90

3. A coal cabinet formed with upper and lower openings provided with swinging closures, a main coal box carried by the upper closure, and having an opening to deliver the material from said box when the latter is within the cabinet, a baffle plate arranged in the cabinet below said main coal box, and adapted to receive the material from the latter, and a coal receiving member carried by the lower closure, and movable therewith, said member being movable into and out of a position relative to the baffle to receive a quantity of coal from such baffle and to serve as a cut off for coal delivery from the baffle, and a drawer 100 105 mounted in the cabinet, and arranged beneath said coal receiving member to receive the coal dust incident to the passage of coal from the baffle to said member. 110

In testimony whereof I have hereunto signed my name.

A. E. ARNOLD.
